UNITED STATES PATENT OFFICE.

ORVAL R. PLATTER, OF NORTH VERNON, INDIANA.

DESIGN FOR A HOUSEHOLD CABINET.

Application filed August 22, 1922. Serial No. 3,513. Term of patent 3½ years.

To all whom it may concern:

Be it known that I, ORVAL R. PLATTER, a citizen of the United States, residing at North Vernon, in the county of Jennings and State of Indiana, have invented a new, original, and ornamental Design for Household Cabinet, as shown in the accompanying drawing and described in the following specification.

The drawing is an elevation perspective view of my household cabinet.

I claim:

The ornamental design for a household cabinet as shown.

ORVAL R. PLATTER.
